CLAIM

The ornamental design for a water tank for a blast hole drill, as shown and described.

DESCRIPTION

FIG. 1 is a front, upper, right perspective view of a water tank for a blast hole drill of our new design.

FIG. 2 is a lower, rear, right perspective view thereof.

FIG. 3 is a front view thereof.

FIG. 4 is a rear view thereof.

FIG. 5 is a left view thereof.

FIG. 6 is a right view thereof.

FIG. 7 is a top view thereof.

FIG. 8 is a bottom view thereof.

FIG. 9 is a front, upper, right perspective view of the water tank for a blast hole drill of FIG. 1 in a second position; and, FIG. 10 is a rear, upper, right perspective view of the water tank for a blast hole drill of FIG. 1 illustrated with the blast hole drill.
